UNITED STATES PATENT OFFICE.

MORRIS HIRSHFIELD, OF BROOKLYN, NEW YORK.

LAMINATED FABRIC.

1,405,511.

Specification of Letters Patent.

Patented Feb. 7, 1922.

Application filed March 3, 1921. Serial No. 449,420.

To all whom it may concern:

Be it known that I, MORRIS HIRSHFIELD, a citizen of the United States, and resident of the borough of Brooklyn, county of 5 Kings, city and State of New York, have invented certain new and useful Improvements in Laminated Fabrics, of which the following is a specification.

My invention relates to foot-wear and 10 more particularly to slippers, and has for its object to provide said slippers with a border which, in addition to the decorative effect produced thereby, will add to the structural stability of the slipper. The particular purpose of the invention is to provide 15 a border of silk or velvet or other woven material constructed in a novel manner so as to prevent ravelling of the edges and thereby avoiding the necessity for binding of any kind and making it possible to 20 utilize the selected material with raw edges. The invention will be fully described hereinafter and the features of novelty will be pointed out in the appended claims.

25 In the accompanying drawings which illustrate examples of my invention without defining its limits, Figure 1 is a face view of the border prior to incorporation in the slipper; Fig. 2 is a rear view thereof; Fig. 3 is a sectional view on the line 3—3 of Fig. 1; and Figs. 4 and 5 are elevations of a slipper illustrating two different types of border.

As shown in the drawings, the border 35 comprises a composite material consisting of a facing of woven fabric 10 such as silk or satin, and a backing of pressed or other non-woven fabric 11 such as felt or other fibrous material. The fabrics 10 and 11 are 40 united preferably by means of a rubber cement 12 in the presence of heat which may be applied either through the medium of an ordinary sad iron or by passing the combined fabrics and the cement between

45 heated rolls and whereby the facing and the backing may be said to be vulcanized together. After the border has been prepared, it may be cut into the required form, for instance as shown in Fig. 1, and may 50 then be attached to the slipper 13, for instance, along the edge of the opening thereof, as shown in Fig. 4 or, if the slipper includes a tongue, the border may also extend along the edge of the tongue, as shown in 55 Fig. 5. The fabric 10 may be either plain,

as shown in Fig. 1, or ornamented, for instance as shown in Fig. 4, or it may be slit periodically, as indicated at 14 in Fig. 5, in which case a ribbon 15 may be threaded through the slits to enhance the ornamental effect of the border and to give the same a distinctive appearance, as illustrated in said Fig. 5. The border may be attached to the slipper in any suitable manner, preferably by sewing the same thereto by lines of 65 stitching 16, as indicated.

The felt or other fibrous or non-woven material 11 becomes firmly united to the silk, satin or other woven fabric 10 by means of the cement 12 under the application of heat and serves to prevent the ravelling of the fabric 10 at the edges, thus doing away with the necessity for binding of any kind or for any other special means whereby the raw edge of the fabric 10 is 70 generally finished to prevent said ravelling. At the same time, the felt 11 in combination with the cement 12 stiffens the fabric 10 to such an extent or, in other words, gives the same sufficient body to make it 80 possible to easily cut the same in any shape by means of suitable cutting dies of the desired form. The border may have any contour desired or predetermined by the type of ornamentation it is desired to incorporate in the slipper, and may be placed in 85 locations thereon other than those illustrated in the drawings; when located as shown, the border, in addition to its functions as an ornamental border, also increases 90 the structural stability of the slipper along the edge thereof which very often has a tendency to collapse because of the inherent flexibility of the material of which the slipper is constructed. As shown in Fig. 5, 95 the border may be combined with other material such as ribbon to impart a distinctive and highly ornamental appearance to the slipper.

The invention is particularly adapted to 100 slippers constructed of felt or similar material and commonly known as bedroom slippers, although it is not limited to this use and may be adapted to slippers of other material and even to foot-wear other than 105 slippers.

It is, of course, obvious that any form of adhesive may be used that will fasten the two parts together so that ravelling will not occur, and therefore the term "cement" is 110

used in its broadest sense to include any adhesives that will produce this result, in the absence of any better generic term.

Various changes in the specific forms shown and described may be made within the scope of the claims without departing from the spirit of my invention.

I claim:

1. A fabric comprising a facing of woven material of the silk type liable to ravel along cut edges, and a coextensive backing of non-woven material cemented to said facing to prevent ravelling thereof along said cut edges.

2. A fabric comprising a facing of woven material of the silk type liable to ravel along cut edges and a backing of felt vulcanized to said fabric by rubber cement to prevent ravelling of said facing along said edges.

3. A fabric comprising a facing of velvet liable to ravel along cut edges and a backing of felt attached to said facing by cement to prevent ravelling of said facing along said cut edges.

In testimony whereof I have hereunto set my hand.

MORRIS HIRSHFIELD.
